[57] CLAIM

The ornamental design for an athletic team flag, as shown and described.

DESCRIPTION

FIG. 1 is a top plan view of an athletic team flag showing my new design. The bottom is plain and unornamented.

FIG. 2 is a front elevational view thereof, the rear elevational view appearing the same.

FIG. 3 is a side elevational view thereof, the other side appearing the same.
